UNITED STATES PATENT OFFICE.

JONATHAN F. AGEE, OF AVONDALE, TEXAS.

COTTON CHOPPER AND CHECKER.

No. 805,110.

Specification of Letters Patent.

Patented Nov. 21, 1905.

Application filed June 8, 1904. Serial No. 211,685.

To all whom it may concern:

Be it known that I, JONATHAN F. AGEE, a citizen of the United States, residing at Avondale, county of Tarrant, State of Texas, have invented a Cotton Chopper and Checker, of which the following is a specification.

This invention relates to cotton-chopping machines, and more particularly to machines provided with revolving disks; and the object 10 is to construct a light machine which will chop or block out the cotton by driving across the rows and block the cotton for five or six feet, or more or less, at one trip across the field, according to the number of disks 15 used on the machine.

One of the advantages of this machine is that it checks the rows of cotton while chopping the cotton. The wheels of the truck are so arranged that the disk next to the cotton that has not been chopped makes a furrow or marks the ground for the path of the wheel which is next to the cotton already chopped on the return trip.

Another advantage of the invention is that 25 the machine is readily convertible to a light cultivator or disk harrow, (which is on wheels.)

Provision is made for adjusting the disks relative to their forward or backward positions relative to each other to prevent the 30 choking of the machine.

Other objects and advantages will be fully explained in the following description, and the invention will be more particularly pointed out in the claims.

Reference is had to the accompanying drawings, which form a part of this application and specification.

Figure 1 is a plan view of the chopper and checker, the seat not being shown in this 40 view. Fig. 2 is a side elevation of the same.

Fig. 3 is a detail view of one of the plow or disk beams. Fig. 4 is a detail view of the adjusting support for one of the beams. Fig. 5 is a broken sectional detail view of the 45 total connections of the adjusting support with the presser-arm.

Similar characters of reference are used to indicate the same parts throughout the several views.

This invention is provided with a rectangular frame in a substantially horizontal position, consisting of the front beam or bar 1, the back beam or bar 2, and the side beams 3, which frame is mounted on the axle 4, and 55 the axle 4 is mounted in the wheels 5. A tongue 6 is attached to the axle 4 by a suit-

able bolt, such as a U-bolt, such U-bolts 7 being used to attach the frame-pieces 3 to the axle 4. The tongue is also attached to the frame-piece 1 by means of the bolt 8. The 60 tongue is braced by the braces 9, which are attached to the tongue by suitable bolts and also attached to the frame-pieces 3 by bolts. A bar or brace 10 is attached to the tongue 6 and to the back frame-piece 2 for mounting the ratchet hereinafter described. A seat 11 is mounted on the axle 4 and the frame-piece 2; but the seat may be transferred at will to the frame-piece 1 and the axle 4. The disks 12 are carried by beams 13, and the 70 disks 14 are carried by beams 15. The beams 13 and 15 have their adjacent vertical sides flush with each other—that is, in the same vertical plane. In the drawings the beams 13 are pivotally mounted on the shaft 16 and the beams 15 are pivotally mounted on the 75 shaft 17. Where the cotton is small and the land is smooth and clear of trash, both sets of beams may be mounted or pivotally attached to the front shaft or to the rear shaft. Each 80 beam is provided with a brace 18. The shaft 17 is journaled in the hangers or braces 19, which are adjustable by reason of several bolt-holes therethrough. The hangers 19 have braces 20. The shaft 16 is journaled in 85 the same hangers 19, but farther to the rear for the purpose of locating the disks 12 farther back than disks 14 to prevent choking of the disks by trash. The shaft 16 is also provided with braces 21, which are attached to beam 1. The shaft 17 is provided with hangers 22, which are attached to the front frame-piece 1. Braces 23 are also provided for making the framework rigid. These braces are mounted on the shaft 17 and bolted 90 to the axle 4.

The beams 13 and 15 are supported and held and adjusted at the proper distance above the ground by the presser-arms 24 and the adjusting-bars 25, with their attachments. The 100 disks are set at the proper angle and mounted on the beams by shoes or castings 26. The castings 26 constitute the bearing for the disks. These castings have grooves formed therein for receiving the beams 13 and 15, and the castings are secured on the beams by 105 suitable bolts. The arms 24 are mounted on a shaft 27, which shaft is square in cross-section. The shaft 27 is journaled in bearings 28, which are bolted to the under side of frame-pieces 3. The shaft 27 passes through 110 the brace-bar 10, which makes this bar more

firm. This shaft is rocked by means of a lever 28' for the purpose of raising or lowering the rear ends of the arms 24. The lever 28' is held at any suitable adjustment by means 5 of the ratchet 29, which ratchet is mounted on the brace-bar 10, and by the spring-pressed dog 30, which engages the ratchet 29. The beams 15 and 13 are supported by the adjusting-bars 25, which are pivotally connected to 10 the arms 24 and to the castings 26, which have upward-projecting bifurcated studs 31. The bar 25 is free to move through the arm 24, or rather the arm 24 is free to move down on the arm 25, but is prevented from upward 15 movement relative to said bar by reason of a key 32, which key may be set in any one of the holes in the bar 25. This is accomplished by pivoting the arm 24 to a clip 33, through which the bar 25 moves loosely. The arm 24 20 is pivoted to the clip 33 by reason of the pins or trunnions 34. A spiral spring 35 is mounted on the bar 25 to hold the beams 13 and 15 down for the purpose of holding the disks at the proper depth in the ground. The disks 25 can thus yield upwardly to some extent, and the pressure can be increased on the disks by lowering the outer ends of the presser-arms 24. The upper end of the spring 35 presses against the clip 33, and the lower end rests on 30 the plate or bracket 36, through which the bar 25 passes loosely. The clip or bracket 36 has an upward-projecting stud 37, which is bent at the upper part to pass through a hole in the bar 25. This clip 36 rests on the stud 31 and supports the spring 35 and prevents it from interfering with the stud 31. The arms 24 are held depressed by the lever 28' through the dog 30 and the ratchet 29. The disks 12 and 14 are set at the proper angle by means of 35 the castings 26. The disks are set at the proper distance apart by the castings or shoes 26, and the distance can be varied by moving the beams 13 and 15 laterally on the shafts 17 and 16. The means for accomplishing this 40 is illustrated in Fig. 3. Between the beam 15 and its brace 18 a cuff or movable collar 38 is on the shaft 17. This collar can be moved to any convenient or desirable position on the shaft 17 and made stationary thereon by means 45 of the set-screw 39. A collar 38 is placed between each beam 13 or 15 and its brace 18. The shaft 16 may be placed in the journal 40 in the brace 19 for varying the position of the disks 12 and 14 relative to each other.

50 This machine has been described as a machine for blocking or chopping cotton. This is done by simply driving the team across the rows of cotton. The object is to have the disks of each pair run about three inches apart, more or less—that is, each pair of disks will leave about three inches of ground not broken, and consequently leaves the growing cotton-plants. I have shown a chopper with four pairs of disks. This number may 55 be increased or diminished without departing

from my invention. The chopper marks the ground over which the return trip must be made. The outside disk makes a furrow in which the inside wheel must run on the return trip. In this manner the machine marks 70 or checks the land.

This machine is readily convertible into a light cultivator or disk harrow on wheels. The only thing to be done to convert the machine is to change the positions of the beams 75 13 and 15 and the arms 24. This is done by moving the arms 13 and 15 along on the shaft 16 or 17 and by moving the arms 24 on the bar 27 and by changing or transposing the positions of some of the disks. 80

Having fully described my invention, what I claim as new, and desire to secure by Letters Patent, is—

1. A cotton chopper and checker comprising a truck, beams in pairs pivotally connected to said truck and capable of forward or backward adjustment, and disks carried by said beams at determined angles, the beams of each pair of beams being parallel and flush with each other for portions of their lengths 85 90 for bracing purposes whereby said disks will be held at constant angles at different forward or backward adjustments.

2. A cotton chopper and checker comprising a truck, pairs of disks, pairs of beams 95 parallel and flush with each other for mounting said disks on said truck, shoes for attaching said disks to said beams at determined angles, means for supporting said beams and permitting yielding motion there- 100 of upward, and means for adjusting the rear disk of each pair of disks forward or backward.

3. A cotton chopper and checker comprising a truck, vertically-adjustable hangers, 105 beams parallel and flush with each other, shafts mounted in and longitudinally adjustable in said hangers for pivotally connecting said beams to said truck, revolving disks mounted on said beams, and means for supporting said disks yieldingly at various adjustments. 110

4. A cotton chopper and checker comprising a truck, beams in pairs provided with means for pivotally attaching the same to 115 said truck at different adjustments, revolving disks, shoes for attaching said disks to said beams at determined angles, said shoes having bifurcated upward-projecting studs, presser-arms operatively connected to said 120 studs, a shaft journaled in said machine for operating said arms, and means for adjusting said arms by means of said shaft.

5. A cotton-chopping machine having a truck, beams carrying revolving disks, shafts 125 for mounting said beams forward or backward relative to each other, hangers for mounting said shafts at vertical and longitudinal adjustments on said truck, shoes for mounting said disks on said beams at determined an- 130

gies, and means for lateral adjustment of said beams.

6. A cotton chopper and checker having pairs of disk-carrying beams, shafts for said beams provided with means for longitudinal and vertical adjustments thereof, said beams being laterally adjustable on said shafts, and means for attaching disks to said beams.

In testimony whereof I set my hand, in the presence of two witnesses, this 28th day of 10 May, 1904.

JONATHAN F. AGEE.
